UNITED STATES PATENT OFFICE

107,671

DESIGN FOR A COIN OPERATED BILLIARD TABLE

Joseph C. Allen, Birmingham, Ala.

Application November 1, 1937, Serial No. 72,544

Term of patent 7 years

To all whom it may concern:

Be it known that I, Joseph C. Allen, a citizen of the United States of America, residing at Birmingham, in the county of Jefferson and State of Alabama, have invented a new, original, and ornamental Design for Coin Operated Billiard Tables, of which the following is a specification, reference being had to the accompanying drawing, forming part thereof.

The figure in the drawing is a perspective view of a coin operated billiard table, showing my new design.

I claim:

The ornamental design for a coin operated billiard table, as shown.

JOSEPH C. ALLEN.
